REFECTORY TABLE

Alfred H. Holland and Robert A. Holland, Winston-Salem, N. C.

Application November 19, 1934, Serial No. 753,716

1 Claim. (Cl. 311—56)

This invention relates to an article of furniture and more especially to an extension table equipped with movable extension leaves for extending the length of the table.

In many forms of extension tables heretofore used the additional leaves have been inserted in the central portion of the table, thereby making it necessary to make the end leaf portions in movable sections in order to accommodate the additional leaves. It is, therefore, an object of this invention to provide additional table leaves which are slidably mounted beneath the ends of the main table top and which may be withdrawn when it is desired to extend the length of the table.

It is a further object of this invention to provide an extensible leaf for a table, desk or the like, with means mounted on said leaf for automatically raising and holding the leaf flush with the top portion of the table. Manual means are also provided for releasing the extension leaf so that it may again be inserted in a suitable recess disposed beneath the end of the table top.

While this invention is particularly adapted for use on tables, it is to be understood that the principle is equally applicable to writing desks, ironing boards, or in fact, to any article of furniture where a leaf is desired to be withdrawn from extended position when not in use.

Some of the objects of the invention having been stated, other objects will appear as the description proceeds when taken in connection with the accompanying drawings, in which:—

Figure 1 is an isometric view of a table made in accordance with the invention;

Figure 2 is a top plan view of the table;

Figure 3 is a longitudinal sectional view taken along line 3—3 in Figure 2 showing the table leaf on one end in an extended position and the table leaf on the other end in a closed position;

Figure 4 is a transverse sectional view taken along line 4—4 in Figure 2;

Figure 5 is a longitudinal sectional view taken along line 5—5 in Figure 2 showing one end of the recesses beneath the table for receiving a table leaf when in closed position;

Figure 6 is an isometric view of a portion of an inverted table leaf support showing means for locking the support in elevated position;

Figure 7 is a top plan view with portions broken away of a portion of a table with a modified form of the invention applied thereto;

Figure 8 is a longitudinal sectional view taken along line 8—8 in Figure 7;

Figure 9 is a view similar to Figure 8 but showing the table leaf in closed position;

Figure 10 is a transverse sectional view taken along line 10—10 in Figure 7;

Figure 11 is a detail sectional view taken along line 11—11 in Figure 7;

Figure 12 is a detail sectional view taken along line 12—12 in Figure 7;

Figure 13 is an isometric view of one of the wedges which is adapted to be mounted on a table leaf support for holding the table leaf in extended position;

Figure 14 is an isometric view of a modified form of table leaf support which is somewhat similar to the form used in Figures 1 to 6 inclusive.

Referring more specifically to the drawings, the numeral 10 denotes an extension table which is supported by legs 11, 12, 13 and 14. The upper ends of legs 11 and 12 are secured together by means of a transverse member 15, and the upper ends of legs 13 and 14 are likewise secured together by means of transverse member 16. A similar longitudinal member 17 is connected to the upper ends of legs 11 and 13, whereas, member 18 connects the upper ends of legs 12 and 14. Suitable braces 19 are used to connect the members 15, 16, 17 and 18 to each other, and these braces are also secured to the upper ends of legs 11, 12, 13 and 14.

Fixedly mounted on top of members 17 and 18 are filler members 25 and 26 respectively which, in turn, have secured to the upper side thereof a conventional table top 27. By placing the filler members 25 and 26 beneath the central portion of the table top 27, and cutting them shorter than the length of the table top, suitable recesses 28 and 28' are provided between the lower side of the table top and the upper side of members 11 and 18 inclusive for the reception of the extension leaves when in closed position.

Transverse member 16 has suitable notches 30 cut therein (Fig. 3), in which are slidably mounted extension leaf supports 31 and 32. These supports are identical in all respects except support 32 is shown in the drawings as being opposite hand to support 31, and, therefore, a description of one will suffice for the other, since the same elements of construction are used in both. Secured to the upper ends of members 31 and 32, 50 by any suitable means such as screws 33 and 33a, is an extension leaf 34 which is shown in extended position in the right-hand portion of Figures 1, 2 and 3. The left-hand end of supports 31 and 32 are slidably mounted in U-shaped stirrup 55

members 35 and 36, said stirrup members being secured to the lower side of table top 27 by any suitable means such as screws 37 and 38 respectively.

5 Secured in the left-hand end of each of supports 31 and 32 is a bracket 45 having an inclined portion 46 which is adapted to engage the bottom of U-shaped members 35 and 36 and raise the left-hand end of supports to a horizontal 10 position when the leaf 34 is being drawn to an extended position. It should be noted that the left-hand end of supports 31 and 32 also have projections 47 integral therewith which limits the movement to the right of the leaf 34 when 15 it has reached its proper position. In Figure 2 these projections are shown engaging the stirrups 35 and 36 when the leaf 34 is in extended position.

Figure 6 shows an enlarged inverted view of 20 the right-hand end of support 31 with the wedge 48 and its associated parts in a released position. The supports 31 and 32 are L-shaped in cross-section and have flanges 50 and 51 integral therewith. The flange 50 holds the upper portion 25 of wedge 48 in position (Fig. 3), while the flange 51 is adapted to slide in a suitable groove 52, which groove is cut in the side of wedge 48, and to hold the wedge in the proper position with relation to the support at all times. Secured to 30 the end of wedge 48 is an angle member 53 by any suitable means such as nails or screws 54. A rod 55 has one end pivotally secured to the outstanding leg of angle 53, and the central portion of said rod is slidably mounted in the outer- 35 standing leg of a second angle member 56 which is secured to the interior of L-shaped support 31 by any suitable means such as welding.

The left-hand end of rod 55, as shown in Figure 6, is bent substantially at right angles and penetrates a slot 57 in the end of support 31. In order to normally force the wedge 48 toward the left-hand end of support 31 (Fig. 6), one end of tension spring 58 is secured to angle member 53 and the other end is secured to angle member 56. 45 When the inclined portion 48a of the wedge 48 is not engaging one of the notches 39 in transverse member 16, the left-hand portion of rod 55, which engages the end of slot 57, acts as a stop to limit the movement to the left of wedge 48 in Figure 6. 50 (See left-hand portion of Figure 3.)

Suitable blocks 65 and 66 are secured to the lower side of leaf 34 by any suitable means such as screws 67 and 68. These blocks not only conceal the ends of supports 31 and 32 but also act 55 as stops against which one may rest one's finger while another finger is being used to engage the end of rod 55 to force wedge 48 to the left in Figure 3 and disengage it from the notch 39 in which it rests in transverse member 16. When 60 the block is pushed to the left enough to clear the member 16 the leaf 34 can be lowered and pushed in the recess 28, (Figs. 2 and 5), where it will assume a position similar to the position of leaf 34' in the left-hand end of Figure 3.

65 A suitable cavity 69 is provided in the lower face of leaf 34 in which one may place the ends of his fingers when it is desired to move the leaf to extended position. When the leaf is pulled 70 to extended position from the position shown in the left-hand portion of Figure 3, the wedge 48 will automatically snap into one of the notches 39 slightly before the leaf has been raised to the final elevated position. When the wedges enter, 75 the leaf will automatically be raised flush with the

top 27 since the springs 58 normally force the wedges 48 in notches 39 at all times.

The left-hand portion of the table is similar in all respects to the right-hand portion which has been just described, and similar reference characters will apply to like parts with prime notations added.

Figures 7 to 13 inclusive show another modified form of the invention in which a slightly different type of support for the extension leaf 34 is used. 10 In this form, extension leaf 34 is secured on top of supports 75 and 76 by any suitable means such as screws 73 and 79 respectively. These supports are slidably mounted in suitable notches disposed in transverse member 16 and the extreme left-hand portions of these members are slidably mounted in similar notches disposed in transverse member 80, said transverse member 80 having its ends secured to the longitudinal members 17 and 18. Each of the members 75 and 76 20 has a pin 81 in the left-hand end thereof which is so located that it will engage the side of member 80 when the extension leaf 34 has been pulled to its extreme left-hand position. These pins will prevent any appreciable clearance from 25 occurring between the right-hand end of table top 27 and the left-hand end of the extension leaf 34.

The left-hand ends of these members 75 and 76 also have an enlarged portion 82 on the lower side thereof which serves to raise the left-hand 30 end of each support 75 and 76 up to a horizontal position when the leaf 34 is in an extended position.

A suitable groove 83 is cut in the lower side of these supports in which is adapted to fit a tongue 35 84 which is integral with the upper side of wedge 85, (Fig. 13). It is seen that by providing a tongue of this type (Fig. 13), that when it engages a groove 83 that the wedge 85 cannot become disengaged from the groove except by sliding out the right-hand end of the groove as shown in Figures 7, 8 and 9.

Wedge 86, which is identical to wedge 85, is disposed in the lower side of support 76 and each of these wedges has a beveled surface 88 on the 45 leading edge thereof which is adapted to engage the notches 39 which are cut in the upper end of transverse support 16 when the table leaf 34 is in extended position.

A transverse rod 89 is adapted to penetrate the 50 wedges 85 and 86, and confined to the central portion of rod 89 (Fig. 12), is a U-shaped bracket 90 which has downwardly extending portions 91 with slots 92 therein which slots are penetrated by the rod 89. The collars 93 are fixedly secured 55 on the rod 89 for confining the U-shaped bracket 90 in its proper position. Secured to member 90 as at 94, is a member 95 which extends to the right (Fig. 7) and is slidably mounted in the transverse member 16 (Fig. 11). A suitable button 96 is secured on the end of rod 95 for manipulating the U-shaped bracket which engages rod 89.

Each of these wedges 85 and 86 is secured to one end of a tension spring 98, said tension spring 65 98 having its other end secured to the transverse member 16. These tension springs normally force the wedges 85 and 86 to the right in the drawings and causes the wedges to act principally in the same manner as the wedges 48 in Figure 3, 70 except that the tension springs in this particular case are secured to the transverse member 16 whereas, in Figure 3, the tension spring is secured to the supports. It is seen that by pushing the button 96, (Figs. 7 and 11), to the left, 75

that rod 89 and wedges 85 and 86 will also be pushed to the left thereby causing the beveled portions 88 of the wedges to be disengaged from the notches 30 in the member 16. When this is done, the table leaf 34 and its associated parts may be lowered and placed in a closed position as shown in Figure 9.

Figure 14 shows a support very similar to that shown in Figures 1 to 6 inclusive, but it should be noted that this is U-shaped in cross-section instead of L-shaped. This support 100 has flanges 101 and 102 which are adapted to engage suitable grooves 103 disposed in opposite sides of wedge 104. Wedge 104 has beveled surface 104a and operates in the same manner as wedge 48 and has an angle member 105 secured thereto by any suitable means such as nails or screws 106. Pivottally secured to the outstanding leg of angle member 105 is a rod 107 which has its central portion slidably mounted in a second angle member 108, said angle member 108 being secured to the interior of support 100 by any suitable means such as rivets 109. The right-hand end of rod 107 is bent substantially at right angles 25 and penetrates the slot 110 in the side of the support.

A tension spring 11 has one end thereof secured to the angle member 105 and the other end of the spring is secured to the angle member 108. This causes the wedge 104 to be pulled to the right at all times and also causes the wedge 104 to engage the notches 30 when the leaf is in extended position. It is seen that the method of releasing the block 104 from the notches 30, is similar in all respects to the method of releasing the wedge 48. By providing the inturned flanges 101 and 102, a more stable support is provided for the wedge 104 as well as presenting a slightly more finished appearance, although it has been found in the cost of construction, that the form shown in Figures 1 to 6 inclusive, is preferable from a manufacturing standpoint due to the simplicity of construction and cost of material.

When the extensible leaves are pulled to extended position and before they are elevated, the leading ends of the blocks 48, 85 or 104, as the case may be, are pulled against the frame of the table, and when the extension leaf is elevated, the blocks will move into position and exert a wedging action to hold the extension leaf in the same plane as the table top. It should be noted

that as the blocks force the slides against the lower surface of the table top that this results in causing the extension leaf and top to be in the same plane, as it is also evident that should either the top or the extension leaf be warped 5 that there would be still an alignment of the meeting edges of the top and leaf to cause all portions of the leaf and the top to be in the same plane. This would not be true if the upward movement of the slides were limited by means 10 other than having the slides fit against the lower surface of the table top.

In the drawings and specification there has been set forth a preferred embodiment of the invention, and although specific terms are employed, they are used in a generic and descriptive sense only, and not for purposes of limitation, the scope of the invention being set forth in the appended claim.

We claim:

In a refectory table having a frame and a top secured to the top of the frame in spaced relation to the top of the frame and providing at each outer edge a space for the nesting of leaves, a pair of slides secured to the lower side of each leaf, and having sliding movement in the frame, the top edges of the frame having notches therein for reception of the slides, each slide comprising a piece of sheet metal bent to form a top and a pair of sides, the lower edge of one side portion being bent inwardly, a wedge-shaped block member mounted for sliding movement in each of said slides below the top thereof and between said sides, said wedge-shaped member having a groove in one side thereof into which the said inturned lower edge of one of said side portions is adapted to project, one of the side portions of each of said slides having a bracket secured to the inner surface thereof, a tension spring having one end secured to the bracket and having its other end secured to said block for normally urging said block between the slide and the frame when the leaves are extended, one of the sidewalls of each of said slides having a slot therein, a rod secured to said block and slidably penetrating 40 said bracket and being bent laterally and penetrating said slot where its end can be engaged to push said block inwardly to permit lowering of the leaf.

ALFRED H. HOLLAND.
ROBERT A. HOLLAND.
